UNITED STATES PATENT OFFICE.

THOMAS LYNCH, OF BROCKPORT, NEW YORK.

WHIFFLETREE.

SPECIFICATION forming part of Letters Patent No. 727,165, dated May 5, 1903.

Application filed December 27, 1902. Serial No. 136,862. (No model.)

To all whom it may concern:

Be it known that I, THOMAS LYNCH, a citizen of the United States, residing at Brockport, in the county of Monroe, in the State of New York, have invented an Improvement in Whiffletrees, of which the following is a specification, reference being had to the accompanying drawings.

My invention relates to an improvement in whiffletrees in which recesses are formed at the ends to receive and conceal the ends of the tugs and the devices for attaching the tugs are simplified and cheapened.

My invention is fully described and illustrated in the following specification and the accompanying drawings, the novel features thereof being specified in the claims annexed to the said specification.

In the accompanying drawings, Figure 1 is a plan view. Fig. 2 is a horizontal section. Fig. 3 represents a modification. Fig. 4 is a transverse section.

My improved whiffletree is made of tubular metal, having recesses at each end in which the ends of the tugs are concealed.

A represents the tubular body of the whiffletree, which may be of any suitable form, preferably rounded or oval, tapering toward the outer ends. At its center the whiffletree is provided with a tube or ferrule to receive the bolt on which it swings.

The whiffletree may be formed of one piece, or it may be jointed in the middle, being strengthened, if preferred, at the middle by a suitable collar, (represented by the dotted lines in Fig. 1.) The ends may also be stiffened by suitable collars, brazed on. The tug F is attached to the end of the whiffletree by the eye D, inserted in an arm C, secured to the whiffletree. The tug is provided with a series of slots E, which receive the eye D, which is inserted in the arm so that it can be turned on its axis. To adjust the length of the tug, the free end of the tug being bent and inserted in the end of the whiffletree, is effectually concealed, thereby producing a better finish and giving an improved appearance. In the modified attachment for the tug (shown at the right in Fig. 1) the eye D is fixed

so that it does not turn in the arm C, and the 50 arm itself is hinged or pivoted to the whiffletree so that it can be swung outward, as indicated by the dotted lines in Fig. 2, to hook up or unhook the tug. In this case a leather strap I is fastened to the arm and has its free 55 end passed through the eye to prevent accidental detachment of the tug. The arm C in this construction also serves to prevent the entrance of mud, dirt, or snow into the end 60 of the whiffletree.

In Fig. 3 my improved whiffletree is shown with a wooden center J, to which the tubular ends may be attached in any suitable manner, such as by screws. In this case the front side of the wooden center is cut away to form a 65 suitable recess for the tug, as shown. The tubular ends may be made of any suitable length.

I claim—

1. The combination with the tubular open-ended whiffletree of means for adjustably attaching the tug thereto adapted to permit the insertion of the free end of the tug into the open end of the whiffletree, as and for the purposes set forth. 70

2. The combination with the tubular whiffletree, of means for adjustably attaching the tug thereto, adapted to permit the insertion of the free end of the tug into the open end of the whiffletree, and to close the opening there- 80 in, as and for the purposes set forth.

3. The combination with the tubular open-ended whiffletree, of the arm attached thereto, the lug or eye inserted in the arm and arranged to permit the adjustable attachment 85 of the tug thereon, while permitting the insertion of the free end of the tug in the open end of the whiffletree, as and for the purposes set forth.

4. The combination with the tubular whiffletree, having means for attaching the tugs thereto, of the pivoted arm carrying the eye, adapted to engage with the slots in the tug, as and for the purposes set forth. 90

THOMAS LYNCH.
